UNITED STATES PATENT OFFICE.

MICHAEL MORRELL, OF BROOKLYN, NEW YORK, ASSIGNOR TO LOUIS MALINA, OF NEW YORK, N. Y.

YARN WINDING.

Application filed February 10, 1926. Serial No. 87,230.

This invention relates to new and useful improvements in yarn windings, and particularly to improvements on the article and method described and claimed in my Patent No. 1,572,157, and my copending application Serial No. 62,575, filed October 15, 1925.

In accordance with the method described in said patent a groove or depression is formed in the yarn winding by bearing 10 with a stationary tool against the yarn while it is being wound on the core, the purpose of the depression being to afford a suitable location for knots in the yarn.

In accordance with the method forming 15 the subject matter of the present invention, the necessity of providing such special tool is avoided by varying the tension on the yarn during a predetermined stage of the winding operation. The tension being increased or decreased when the yarn is being 20 wound on a certain section of the core or cone, the yarn lengths within that section will be wound tighter and will therefore lie below the level of the balance of the yarn 25 within the same layer. This increase or decrease in the tensioning may be most expeditiously obtained by varying the position of the standard yarn guide provided on cone winding machine. Furthermore, 30 the depression may be accentuated or, to a certain extent, produced solely by bearing with the yarn guide against that portion of the yarn which it is desired to depress.

While the depression in the yarn may be 35 effected with the usual type of cone, I have found that a deeper depression may be obtained if a core of the type described in my said copending application is used. Instead of forming a narrow groove or depression 40 in the paper cone or other core, a wide groove or depression is formed in this core, preferably extending all the way to the apex of the core. It is easier thus to depress a paper cone and furthermore, a wider depression is obtained which will give the operator more space within which the knots 45 may be placed.

In order more clearly to set forth the 50 nature of the present invention I shall describe a preferred embodiment thereof. It should be understood, however, that yarn windings of the nature described and claimed in my said patent may be produced by a number of other methods and also that

the details of the mechanism herein disclosed may be varied within a wide range without departing from the spirit of the invention.

In the drawings, Fig. 1 is a front elevation of as much of a cone winding machine 55 as is necessary for a clear understanding of the invention;

Fig. 2 is a side elevation of the machine; Figs. 3 to 7 illustrate modifications of the thread guide control, Figs. 3—5 being horizontal cross-sections and Figs. 6 and 7 front and rear views, respectively, of the carriage.

Fig. 8 is an elevation of a partly wound cone; and

Fig. 9 is an elevation of a modified form 70 of a partly wound cone.

A paper cone 1 having a corrugated surface is clamped in the usual manner on the cone holder 2 of a winding machine. Near its apex the surface of the cone is narrowed 75 as indicated at 3 (Fig. 8). By means of a lever 4 the cone 1 is clamped in place and rotated through a shaft 5 which in turn is driven by the usual driving means including a belt 6. A thread of yarn 7 is fed to the cone from a supply 8 through a suitable tension controlling mechanism 9. The yarn 7 then passes through a V-shaped groove 10 provided in the upper part of a porcelain button 11 and thence is wound directly on 80 the cone 1. The porcelain button 11 is carried at the upper end of an arm 12 of resilient material. The arm 12 is fastened to a rod 13 which is mounted in the lower part of a carriage 14 in a manner to permit its 85 travel back and forth in a horizontal direction. Reciprocatory motion is imparted to rod 13 by means of a shaft 15 carrying a cam 16 and suitably geared to the driving motor. Since the details of this construction are well known in the art, their full description and illustration will be dispensed with.

The carriage 14 is provided with a weighted arm 17 having a hub 18 which is rotatably mounted on the cam housing 19. 100 The carriage 14 may be rotated around the pivot point constituted by 18 and thus moved to and from the cone 1. By means of a spring 20, also mounted on the cam housing and bearing against the weighted end 21 of the lever 17, the carriage 14 will be maintained in any position into which it may be moved by hand. However, the 105

spring 20 permits the carriage 14 gradually to move away from the cone in the customary manner as the winding thereon becomes thicker.

- 5 By rotating the carriage towards the cone 1 the porcelain button 11 is carried with it. Since the carriage has a fixed pivot point, the rotation towards the cone will result in raising it with respect to the cone. The raising of the button with respect to the cone will increase the tension of the yarn 7 fed through the groove 10. The spring arm 12 is so tensioned that it firmly lies against the carriage 14 and the thread is guided in 15 such a manner that it will be wound at a predetermined tension on the cone 1 back and forth over a certain area thereof. As best shown in Fig. 8, during the operation of the machine the button 11 being held 20 against a carriage 14, does not quite touch the yarn winding on the cone 1 and, up to a certain point, remains always in the same position with respect to the cone. However, when the button 11 reaches a point opposite 25 the depressed apex 3 of the cone, it will be moved towards the cone and therefore slightly raised with respect to the position it occupies during the balance of its travel. This is accomplished owing to the provision of a 30 steel spring 22 riveted at 23 to the carriage 14. The spring is so bent that the spring arms 12 carrying the button will glide on top of this spring and will be held by it away from the carriage and pressed against 35 the cone.

Instead of this arrangement, any number of other arrangements such as the ones illustrated in Figs. 3 to 7 may be provided. In Fig. 3 the carriage 14 is shown as having a 40 raised cam-like end 23 on which the arms 12 may ride. In the arrangement shown in Fig. 4 a bent spring 24 is fastened to the free end of the carriage 14, the end of the spring lying within a notch 25 provided in the carriage. In the arrangement shown in Fig. 45 5, a suitably bent wire 26 is mounted on the end of the carriage. In accordance with the arrangement shown in Fig. 6, instead of mounting a spring like 22 on the carriage 50 14, a leaf spring 30 is fastened with one end to the rear of arm 12. The free end of spring 30 bears against the carriage 14 and tends to push the guide towards the cone. However, such forward movement of the 55 guide is limited by a rod 31 mounted on the carriage 32. The yarn guide reciprocates between rod 31 and carriage 14, and when it reaches near the apex of the cone where the depression is to be formed, it follows an 60 outwardly bulging part 33 of the rod and thus approaches the cone and is raised with respect thereto. In the modification illustrated in Fig. 7, that part of the carriage 14 which is opposite the depressed apex of 65 the cone is cut away as indicated at 34. A

wire frame 35 is fastened to the rear of the carriage at 36 to afford a friction surface for the yarn guide. A spring 37 is mounted on the carriage 14 by means of a bolt 38 which projects through a longitudinal slot 39 in the spring so as to permit the longitudinal adjustment of the latter. The forwardly bent end 40 of spring 37 projects in front of the opening 34 and overlaps the end of a spring 41 mounted on the front of the carriage 14 at 42. The bulge in spring 40 will control the forward movement of the guide during its reciprocatory movement. By varying the adjustment of spring 37, the width of the depression in the yarn winding as well as the pressure on the guide may be controlled to suit operating conditions.

Owing to the fact that while the guide button 11 is travelling back and forth opposite the depressed end 3 of the cone the yarn 7 is wound at a greater tension than during the balance of the reciprocatory movement, that portion of each layer of the yarn which overlies the depressed end 3 of the cone will be maintained in a lower level than the balance 90 of the layer. The depression of the yarn winding within this area is accentuated by the depression in the paper cone and also by the contact of the button 11 with the yarn winding. However, as shown in Fig. 7, the 95 required depression may be obtained with a cone having a level surface and, of course, other means may be employed for varying the yarn tensioning.

It will be obvious to those skilled in the art that the width, depth or position of the depressed or grooved winding area may be varied to suit operating requirements and that the other features of the machine and method herein described may also be varied 100 without departing from the spirit of the present invention.

What I claim is:

1. The method of winding yarn on a core which consists in increasing the tension 110 on the yarn while it is being wound on a certain section of the core so as to produce a depressed area in the winding, and placing knots within said area.

2. The method of winding yarn on a core which consists in increasing the tension on the yarn while it is being wound on a certain section of the core whereby the yarn winding concentric with said certain section will be depressed with respect to the balance of the winding, and placing knots within the depressed section of the yarn winding.

3. The method of winding yarn on a core which consists in bearing with a tool against the core during the winding of the yarn thereon and reciprocating said tool with respect to the core whereby a depression will be produced in each layer of yarn, and placing the knots by which yarn ends are fastened together within said depression.

4. The method of winding yarn on a core which consists in bearing with a tool against the core during the winding of the yarn thereon and increasing at the same time the tension on the yarn, whereby a depression will be produced in each layer of yarn, and placing the knots by which yarn ends are fastened together within said depression.
5. The method of winding yarn on a core which consists in bearing with a tool against the core during the winding of the yarn thereon, reciprocating said tool with respect to the core, increasing the tension of the yarn while it is being wound on a certain section of the core, whereby a depression will be produced in each layer of yarn, and placing the knots by which yarn ends are fastened together within said depression.
6. The method of winding yarn on a core which consists in bearing with a reciprocating tool against the core during the winding of the yarn on a certain section of the core, increasing the yarn tension while it is being wound on said certain section of the core, whereby a depression will be produced in each layer of yarn, and placing the knots by which yarn ends are fastened together within said depression.
7. The method of winding yarn on a core which consists in depressing the core surface increasing the tension on the yarn while it is being wound on a depressed portion of the core so as to produce a depressed area in the winding, and placing knots within said area.
8. The method of winding yarn on a core which consists in depressing the core surface at one end of the core, increasing the tension on the yarn while it is being wound on the depressed end of the core, whereby the yarn winding concentric with the depressed section will be depressed with respect to the balance of the winding, and placing knots within said depressed section of the yarn winding.
9. As a new article of manufacture, a core for a yarn winding having a depression extending to one end thereof, said depression insuring the formation of a corresponding depression in the yarn winding within which knots may be placed.
10. As a new article of manufacture, a cone for a yarn winding having its apex depressed with respect to the balance of the cone, said depression insuring the formation of a corresponding depression in the yarn winding within which knots may be placed.
11. As a new article of manufacture, a yarn winding in which at a predetermined point in each layer of the winding the yarn is under a greater tension than in the balance of the same layer, whereby a depression is formed in the winding within which knots may be placed.
12. In a yarn winding machine, a core, means for rotating said core, a guide through which yarn under tension passes to said core, means for moving said guide during the winding operation for distributing the yarn on said core, and means for actuating said guide to increase the tension on the yarn while it is being moved on a certain section of said core, whereby a depression is formed in the winding within which knots may be placed.
13. In a yarn winding machine, a core, means for rotating said core, a guide through which yarn under tension passes to said core, means for moving said guide during the winding operation for distributing the yarn on said core, said moving being in a direction substantially parallel with the axis of said core, and means for moving said guide so as to increase the tension on the yarn during the winding thereof on a certain section of said core, whereby a depression is formed in the winding within which knots may be placed.
14. In a yarn winding machine, a core, means for rotating said core, a guide through which yarn under tension passes to said core, means for moving said guide during the winding operation for distributing the yarn on said core, said movement being in a direction substantially parallel with the axis of said core, and means for moving said guide towards said core during the winding of the yarn on a certain section thereof so as to increase the tension on the yarn, whereby a depression is formed in the winding within which knots may be placed.
15. In a yarn winding machine, a core, means for rotating said core, a guide through which the yarn passes to said core, means for moving said guide during the winding operation for distributing the yarn on said core, said movement being in a direction substantially parallel with the axis of said core, and means for moving said guide towards said core and vertically with respect to the axis thereof during the winding of the yarn on a certain section of the core.
16. In a yarn winding machine, a core, a flat surface substantially parallel with the longitudinal axis of said core, a guide for yarn under tension lying against said surface, means for rotating said core, means for reciprocating said guide for distributing the yarn on said core, and a projection on said surface in the path of said guide to move said guide so as to increase the tension on the yarn.
17. In a yarn winding machine, a core, a flat surface substantially parallel with the longitudinal axis of said core, a guide for yarn under tension lying against said surface, means for rotating said core, means for reciprocating said guide for distributing the yarn on said core, and a spring for

pressing said guide away from said surface during a portion of its movement so as to increase the tension on the yarn.

18. In a yarn winding machine, a core, a flat surface substantially parallel with the longitudinal axis of said core, a guide for yarn under tension lying against said surface, means for rotating said core, means for reciprocating said guide for distributing the yarn on said core, and a spring mounted on said surface in the path of said guide to move said guide so as to increase the tension on said yarn.

19. In a yarn winding machine, a core, a flat surface substantially parallel with the

longitudinal axis of said core, a yarn guide lying against said surface, means for rotating said core, means for reciprocating said guide for distributing the yarn on said core, a spring having one end adjustably mounted on said surface, the free end of said spring projecting in the path of said guide, and a second spring mounted on said surface and engaging the free end of said first mentioned spring.

In testimony whereof, I have signed my name to this specification, this 5th day of February 1926.

MICHAEL MORRELL.
